COMBINED WRIST WATCH AND COVER THEREFOR

David Taylor, New York, N. Y.

Application June 11, 1957, Serial No. 46,544

Term of patent 14 years

(Cl. D42—8)

Fig. 1 is a perspective view of a combined wrist watch and cover therefor showing my new design;

Fig. 2 is an exploded perspective view of the watch and cover portion;

Fig. 3 is a top plan view with the cover removed, and Fig. 4 is a bottom plan view thereof.

The characteristic feature of my design resides in the cover portion.

I claim:

The ornamental design for a combined wrist watch and cover therefor, substantially as shown and described.
